(57) **CLAIM**

We claim the ornamental design for a compressor-distractor for the foot, as shown and described.

DESCRIPTION

FIG. 1 is a perspective view of a compressor-distractor for the foot showing my new design;

FIG. 2 is a front view thereof;

FIG. 3 is a rear view thereof;

FIG. 4 is a left side view thereof;

FIG. 5 is a right side view thereof;

FIG. 6 is a top view thereof; and,

FIG. 7 is a bottom view thereof.

The dot-dash broken lines and evenly dashed broken lines adjacent the claim define the bounds of the claimed design and form no part thereof. The remainder of the evenly dashed broken lines shown on FIGS. 1-7 illustrate portions of the compressor-distractor for the foot that form no part of the claimed design.
